(57) **CLAIM**

The ornamental design for a display screen with animated icon, as shown and described.

DESCRIPTION

FIG. 1 is a first image in a sequence for a display screen with animated icon;

FIG. 2 is a second image in the sequence for the display screen with animated icon;

FIG. 3 is a third image in the sequence for the display screen with animated icon; and,

FIG. 4 is a fourth image in the sequence for the display screen with animated icon.

The broken lines show the display screen and form no part of the claimed design.

The appearance of the animated image sequentially transitions between the images shown in FIGS. 1–4. The process or period in which one image transitions to another image forms no part of the claimed design.
